UNITED STATES PATENT OFFICE.

RUDOLPH HOFFMAN, OF KANKAKEE, ILLINOIS, ASSIGNOR TO SEARS, ROEBUCK AND CO., OF CHICAGO, ILLINOIS, A CORPORATION OF NEW YORK.

COMBINED HOT PLATE AND LAUNDRY STOVE.

Application filed June 6, 1921. Serial No. 475,501.

To all whom it may concern:

Be it known that I, RUDOLPH HOFFMAN, a citizen of the United States, residing at Kankakee, in the county of Kankakee and 5 State of Illinois, have invented certain new and useful Improvements in Combined Hot Plates and Laundry Stoves, of which the following is a specification.

The invention relates to a gas heating appliance, and has for its aim the provision of such an appliance capable of use as a hot-plate, which is adapted to be supported upon a table or the like and is readily portable, and which is also capable of use as a laundry 10 stove, being for this latter purpose provided with a detachable stand for supporting it a substantial distance above the floor as in the case of ordinary stoves.

A further object of the invention is to 15 provide a heating appliance of the character stated which is of a very practical character.

In the accompanying drawings wherein I 20 have illustrated a preferred embodiment of my invention, Figure 1 is a front elevation 25 of the improved heating appliance. Fig. 2 is a perspective view of one of the end brackets and supporting members providing the legs for the hot plate. Fig. 3 is a frag- 30 mentary horizontal section taken in the plane of line 3 of Fig. 5. Fig. 4 is a frag- mentary transverse sectional view taken in the plane of line 4 of Fig. 1. Fig. 5 is a fragmentary vertical longitudinal sectional 35 view. Figs. 6 and 7 are detached perspective views of the burner supporting bar and one of the tray supporting members for the usual catch or drip pan.

The device comprises generally a rectangular frame 8 having at each end a pair of 40 supporting members or brackets 9 and an extension support or stand comprising a plurality of legs 10 connected at their lower ends by means of a flanged plate 11 and de- 45 tachably secured at their upper ends to said end members.

The stove frame 8 is preferably made 50 from sheet metal bent into channel form, and the end members are also formed of sheet metal and each comprises an end wall 9^a and two side walls 9^b providing a pair of depending angular portions 12 constituting 55 supporting members for the frame. Said end members may be secured to the under side of the frame 8 by means of bolts

13 entered through out-turned side flanges 14 and end flanges 15. The lower ends of the angular portions 12 are bent to provide feet 16, the metal being bent back upon itself for this purpose. 60

The legs 10 of the supporting stand for the stove are made angular in form, with their upper ends conforming to the shape of the angular portions 12 of the supporting members 9; and the upper portions of 65 the legs are fastened to the angular portions 12 by means of bolts 17 entered through registering apertures provided in the legs and in the member 9 at vertically spaced intervals. Preferably the legs are 70 arranged to fit over the outer corners of the supporting members, with their upper ends abutting the under side of the frame 8. As shown at 18 in Fig. 3 the opposite edges 75 of the legs 10 are bent inwardly and back upon themselves to form stiffening means for the legs.

The plate 11, which serves to connect the lower ends of the legs together, is formed from a single sheet of metal having down- 80 turned flanges which are secured to the walls of the legs by means of bolts 19. The plate 11 thus constitutes a bracing means for the stand.

A suitable number of burners 20 (two being herein shown) are mounted beneath the usual grids 21, the latter being removably supported by the frame 8 in the usual way. The means for supporting the burners may comprise a channel bar 22 extending longitudinally of the frame and having its opposite ends fastened in the end members 9. Such fastening for the ends of the bar may be of any suitable character, but preferably is of such a nature as to render the bar re- 85 movable at will. One form of means for this purpose comprises a bracket 22^a secured upon the inner sides of the supporting members 9 and comprising an inwardly extending portion 23 and a downturned portion 90 24. The portion 24 is notched as at 25 to receive the end of the bar 22, while the latter is provided with laterally extending lugs 26 for engagement with the depending portion 24 of the bracket 22^a whereby de- 100 tachably to secure the bar in position upon said bracket.

A gas manifold 27 is suitably mounted at the forward side of the stove by means of brackets 28, secured at their inner ends to 110

the under side of the frame 8 as by means of bolts 29. One end of said manifold is provided with a fitting 30 for the reception of a flexible gas conductor in a well known manner, and the burners are provided with valve connections 31 with the manifold.

Preferably a pan 32 is provided for the purpose of collecting refuse such as matches and the like. This pan is also supported by the end members 9 (Figs. 5 and 7), and for this purpose I provide a pair of supporting members or brackets 33 secured to the supporting members and adapted to removably support the pan 32. As shown in said figures, each of said brackets 33 is formed from a single sheet of metal to provide a main or top plate 34 having downturned end flanges 35 and side flanges 36 and 37. The downturned side flanges 35 and the outer flange 36 are respectively secured to the opposite side walls of the end members 9 and the end wall thereof. The side flange 37 on the inner edge carries a horizontal inwardly extending flange 38 which provides a support for the pan 32, and the ends of said flange 38 are upturned as at 39 to provide retaining lugs for the pan. It will be evident that by this construction the upper edges of the edge flanges of the pan lie substantially flush with the plates 34 of the supporting members.

It will be seen that the appliance is readily adapted for use as a hot plate, the supporting stand consisting of the legs 10 and the connecting plate 11 being for this purpose removed. Thus the angular portions 12 constitute legs for supporting the hot plate upon the table or other support. At the same time the device is readily convertible into a stove, which is especially adapted for use as a laundry stove, by attaching the stand to the angular portions 12 of the supporting members. The construction is of an exceedingly simple character and the stove in either form is exceedingly rigid.

While I have herein illustrated and described the invention with reference to a single embodiment, it will be understood that various changes in form, construction and arrangement may be made without departing from the spirit and scope of the invention as expressed in the appended claims.

55 I claim as my invention:

1. A combined hot plate and laundry stove comprising a frame, a pair of supporting members at the opposite ends of said frame and secured directly to the under side thereof, each of said members providing two angular supports, and a pair of legs angular in form and detachably secured to each of said supports, said legs being adapted to fit over the corners of said supports.

65 2. A device of the class described comprising

ing in combination, a rectangular frame forming a stove top, a pair of end members each formed from an integral sheet of metal and providing two angular corner portions, said members being rigidly secured directly to the under side of said frame, and a plurality of supporting legs also formed of sheet metal and detachably secured to said corner portions.

3. A heating appliance comprising, in combination, a frame made of sheet metal adapted to form a support for a grid, and a pair of supporting members also formed of sheet metal and bent to provide side and end walls constituting two angular supports for the frame, said supporting members being secured at their upper ends directly to the underside of the frame.

4. A heating appliance comprising, in combination, a frame made of sheet metal and of channel formation, and a pair of supporting members also formed of sheet metal and bent to provide side and end walls each having at its upper end a flange secured to the under side of the frame within the channel thereof, said end and side walls of the supporting members constituting angular supports for the frame.

5. A heating appliance comprising, in combination, a frame made of sheet metal and of channel formation, a pair of supporting members also formed of sheet metal and bent to provide side and end walls each having at its upper end a flange secured to the under side of the frame within the channel thereof, said end and side walls of the supporting members constituting angular supports for the frame, and a stand to which said angular supports are detachably secured.

6. A heating appliance comprising, in combination, a frame made of sheet metal and of channel formation, a pair of supporting members also formed of sheet metal and bent to provide side and end walls each having at its upper end a flange secured to the under side of the frame within the channel thereof, said end and side walls of the supporting members constituting angular supports for the frame, and means detachably secured to the opposite supporting members and providing a support for the burners of the stove.

7. A gas hot plate comprising, in combination, a rectangular frame providing a support for grids or the like, a pair of brackets secured at the opposite ends of said frame upon the under side thereof and serving to support the hot plate, and a bar detachably supported at its opposite ends in said brackets to provide a support for one or more burners.

8. A heating appliance comprising, in combination, a rectangular frame providing a support for grids or the like, a pair of

- supporting members secured at the opposite ends of said frame upon the under side thereof, a bar detachably supported at its opposite ends in said members and providing a support for one or more burners, and a detachable connection between said bar and each of said end members comprising a bracket secured to the end member and having a horizontal inwardly extending portion 5 and a depending flange, said flange being provided with a notch for the reception of the end of said bar and said bar having one or more ears bent to retain the bar in said slot.
- 15 9. In a heating appliance of the character described, the combination of a pair of end plates and a channel bar providing a support for one or more burners, said plates having slots adapted to receive the ends of 20 said bar, and lugs formed upon the ends of the bar for engaging the plates whereby to prevent the accidental withdrawal of the bar.
10. In a heating appliance of the character described, the combination of a pair of end plates, means providing a support for a refuse pan comprising a pair of supporting brackets rigidly secured to said end plate and each having an angular portion adapted to receive one end of the pan. 25
11. A portable heating appliance comprising, in combination with a top having depending supporting members, means providing a support for a plate beneath said top comprising a pair of brackets each providing an angular portion adapted to receive one end of said plate, with means at the ends of said angular portions providing retaining means for said plate. 30
- 35

In testimony whereof, I have hereunto set 40
my hand.

RUDOLPH HOFFMAN.
